UNITED STATES PATENT OFFICE.

CHARLES I. WILLIAMS, OF UTICA, NEW YORK.

APPARATUS FOR DRYING OUT MOLDING-FLASKS.

No. 896,070.

Specification of Letters Patent. Patented Aug. 11, 1908.

Application filed February 11, 1905. Serial No. 245,268.

To all whom it may concern:

Be it known that I, CHARLES I. WILLIAMS, a citizen of the United States of America, residing in the city of Utica, Oneida county, 5 State of New York, have invented an Improved Apparatus for Drying Out Molding-Flasks, of which the following is a specification.

The object of this invention is to provide a 10 new apparatus for drying out the sand in molding flasks preparatory to casting, whereby the usual drying oven may be dispensed with.

In carrying out the invention, I provide an 15 individual heat-producing unit capable of being inserted into a sand molding flask and I leave it there until the sand has been dried; then I remove the unit and proceed with the usual method of casting. This heating unit 20 may be an electric one, a gas-burning, or a gas-injecting device, a steam-heated device, or any device which is adapted to produce heat locally within the interior of the mold, and which may be removed from it.

25 In the accompanying drawings I have shown various forms of heating units adapted for use in carrying out this invention.

Figure 1 shows an electrical heating-device within a pipe molding flask, shown in half for 30 purpose of illustration; Fig. 2 shows a plain gas-burning device; Fig. 3 shows a gas-injecting and burning means; Fig. 4 shows a steam-heated device; Fig. 5 illustrates a method which may be used with pipe molds 35 for drying out a number at a time.

I have illustrated my invention as applied to pipe molding flasks, and it is thus described throughout my specification merely because my invention is particularly applicable for that type of molding flask.

In Fig. 1 the flask F is as usual lined with wet sand 2. It is generally placed on end in a casting pit after being dried in an oven. I may place it there before drying according to 45 my present invention. Wherever it is, in the pit or outside, I insert a heat-producing unit P into the interior of the flask, being careful not to disturb the sand while thus inserting it. In this Fig. 1, the unit P consists of a 50 coil of wire c adapted to be heated by an electric current. The coil if supported by a

cover support S provided with vents v for steam or vapor, and a hook h to enable the usual foundry crane to handle the unit.

In Fig. 2 the unit P' consists of a cover 55 support S' provided with a yoke h' and carrying on its underside a number of burners b supported on the pipe P which passes out of the cover and supplies some hydrocarbon mixture to the burners. To prevent the 60 flames from impinging directly upon the sand, I may provide an enveloping cylinder C secured at its top to the support S' and provided with numerous openings o in its walls.

In Fig. 3 I have shown the heating unit P² 65 as an injector I, the flame of which is caused to shoot through the cylindrical mold. If desired this form of heating means may also be provided with a support S² and it may carry a cylindrical interior guard C' as shown 70 in dotted lines for the purpose described in reference to Fig. 2.

In Fig. 4 I have shown a heat-producing unit P³ consisting of a hollow double-walled drum D through which steam may be circu- 75 lated through steam pipes p¹ p².

In Fig. 4 I have illustrated a number of molds m placed one on another. It will be obvious that any one of the heating units before described may be placed within such 80 superposed molds, and the method may then be carried out for the number of molds instead of with a single mold as described.

The advantage of the single mold and its individual heating unit is that I am enabled 85 to place the flasks in their proper position on the floor of the casting pit, there drying them and not be compelled to again handle them before inserting the cores and casting.

I claim as my invention 90

In combination with a sand molding flask, a cover support having steam vents and a carrying hook, electric heating coils passing therethrough and adapted to enter the interior of the flask, substantially as described. 95

In testimony whereof I have signed my name to this specification, in the presence of two subscribing witnesses.

CHARLES I. WILLIAMS.
